UNITED STATES PATENT OFFICE.

RUDOLPH W. GLASNER, OF CHICAGO, ILLINOIS, AND FREDRICH J. RODE, OF CLEVELAND, OHIO, ASSIGNORS TO MARQUETTE TOOL & MANUFACTURING CO., OF CHICAGO, ILLINOIS, A CORPORATION OF ILLINOIS.

BLANK-HOLDING MEANS.

Application filed May 18, 1923. Serial No. 639,810.

To all whom it may concern:

Be it known that we, RUDOLPH W. GLASNER, residing at Chicago, in the county of Cook and State of Illinois, and FREDRICH J. RODE, residing at Cleveland, in the county of Cuyahoga and State of Ohio, both citizens of the United States, have invented certain new and useful Improvements in Blank-Holding Means, of which the following is a specification.

The present invention relates in general to metal stamping presses of the type known as double acting presses, but more particularly the invention relates to the blank holding means therefor.

Heretofore in presses of this kind it was necessary, and in fact only possible to set what is known as the blank holder for a fixed extent of travel with respect to the work supporting surface and after it was once set, the extent of distance of travel would not change during the operation of the press and furthermore it would always have a tendency to travel the same distance under all conditions, often resulting in serious damage if anything should attempt to reduce the extent of such travel during the operation of the press.

To overcome these difficulties and objections and to provide improved means whereby the blank holder would be subjected to a given pressure rather than to be set for a predetermined length of travel, is one of the objects of the present invention.

In practice it is found that metal sheets vary greatly in thickness and also that the sheets being operated upon vary in thickness while they are being drawn into shape. It is therefore another object of the present invention to provide an improved blank holder which, while exerting a certain pressure upon the blank, will still be flexible enough to allow for such variations of thickness of the metal which take place during such operation.

It is further an advantage to provide means whereby the pressure exerted upon the blank may be changed during the different stages of the drawing operation during one cycle of operation of the press.

Heretofore in drawing presses of this kind

the amount of pressure exerted upon the blank by the blank holder merely depended upon the extent of travel of the blank holder, and which travel was always fixed or constant. Under these conditions it will be manifest that it was necessary to adjust the mechanism so as to vary the extent of movement of the blank holder for the varying thicknesses of the work. In the event that the blank holder was adjusted for a predetermined thickness of metal and a sheet of material of a greater thickness was fed through the machine, it will be manifest that considerable damage would be caused either to the work or the machine or both, and in case a thinner sheet was fed through the machine, the work would wrinkle.

Furthermore, as the thickness of the material during the shaping or forming operation varies owing to the flow of material from one part of the material being operated upon to another part, two or more operations have heretofore been necessary for shaping or forming certain articles.

Heretofore in the construction of presses of this kind toggle motions or cams have been employed and which toggle motions do not cause a perfect or clearly defined dwell of the blank holder against the material during the forming operation. It is important in drawing sheet metal shapes to hold the metal at a desired pressure for a given length of time and serious difficulties have been experienced by the heretofore short dwell, which was not controllable but was fixed with relation to the position, lengths and shapes of the toggles or cams and their movements.

It is one of the objects of the present invention to provide improved means whereby the pressure upon the work to be drawn into shape may be predetermined and, at the same time will be flexible.

Another object is to provide improved blank holding means which will readily lend itself to the formation of various shapes out of sheet metal of varying thicknesses and at the same time exert a predetermined pressure upon such varying thicknesses of the sheets.

Another object is to provide improved

blank holding means which will exert a desired pressure upon the blank and compensate for such variations in thickness of the metal to be drawn as are taking place in the metal during the drawing operation.

Another object is to provide an improved blank holder which will provide a clearly defined and extended dwell of the blank holder against the material to be formed, the extent of such dwell being predetermined at will.

Another object is to provide an improved blank holder which will exert a yielding pressure upon the blank to compensate for varying thicknesses of the metal taking place during the operation of forming.

Another object is to provide an improved blank holder by means of the use of which the amount of pressure upon the blank may be variable at will.

Another object is to provide an improved blank holder in which the amount of pressure may be varied at will during the forming operation and during the cycle of operation of the press.

Another object is to provide an improved blank holder by means of the use of which various pressures may be exerted upon the blank during one cycle of operation, such pressure variation being produced automatically and at predetermined periods during such cycle of operation.

Another object is to provide an improved blank holder and means for releasing the pressure upon the blank during a predetermined stage of the forming operation.

Another object of the present invention is to provide an improved blank holding means moving independently of the forming block and means for allowing for variations of pressure by said blank holder upon the metal sheet to be formed.

To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating this invention, and in which

Figure 1 is a view partly in elevation, partly in section and with parts omitted of a press having a blank holding means constructed in accordance with the principles of this invention applied thereto.

Figure 2 is an enlarged detail view partly in elevation, partly in section and partly broken away of a link motion for operating one of the die members.

Figure 3 is an end elevation of Figure 2.

Figure 4 is a view of a portion of a press having a modified form of blank holding means applied thereto.

Figure 5 is a diagrammatic view of the

cushioning device and the controlling mechanism therefor.

Referring more particularly to the drawings the numeral 10 designates the bed of a press supporting the die member 11, 12 indicates a ram carrying a punch member 13 and reciprocable by means of links 14. The press is also provided with a reciprocating blank holding member 15, to which a blank holder 16 is connected. All of these parts are of the ordinary and well known construction in double acting presses.

The blank holding member 15 is reciprocable by means of a crank arm 16^a, between which crank arm and the blank holding member links are arranged so that as the crank arm 16^a is rotated the links will cause the blank holding member to be reciprocated.

In machines of this type any number of links may be provided but four are preferably used and in the present invention as the construction and operation of each of the links is the same, the description of one will apply equally as well to them all.

The link is of a sectional construction embodying members 17 and 18, which are pivotally connected intermediate the ends of the member 18 as at 19. One end of the link 18 is pivotally connected as at 20 with the crank arm 16^a. The other end of the member or section 17 is pivotally connected as at 21 with the blank holding member 15. The members or sections 17-18 of the link are adapted to move about the pivot 19 with respect to each other and any suitable means may be provided for controlling the extent of such relative movement, such for instance as a fluid pressure cushion designated generally by the reference numeral 22. This cushion may be secured to the link in any suitable manner such as by means of anchor rods 23 and the cushion member includes any desired number of chambers which are out of communication with each other.

In the form of the invention shown in Figures 1 and 2, the cushion includes two chambers 24-25 separated by a partition or head 26. Within the chamber 25 is arranged a piston 27 and within the chamber 24 is arranged a piston 28. These pistons are connected by means of a piston rod 29, which passes through the partition 26 and a suitable packing or stuffing box 30 may be provided for forming a fluid tight joint. The free end of the piston rod 29 is connected with the end 31 of the section 18 of the link preferably by means of a supplemental link 32 pivotally connected as at 33 with the link section 18 and is also pivotally connected as at 34 with the end of the piston rod 29, so that when the pistons are moved within the cylinder or cushion 22 the sections 17-18 of the link will be rocked with respect to each other about the pivot 19 and

the section 18 will also be rocked about its pivot 20, while the section 17 will be rocked about its pivot 21.

Fluid pressure may be supplied to the 5 cushion from any suitable source and to that end there is provided a pipe 35, which communicates with a passage 36 in the head of the cushion and has communication with the interior of the chamber 24 on one side 10 of the piston 28. Another pipe 37 communicates with the passage 38 in the partition 26 and communicates with the chamber 25 on one side of the piston 27 and another pipe 39 has communication with the chamber 25 on the side of the piston 27 opposite to the side on which the pipe 37 communicates with the chamber 25.

It will thus be seen that when fluid pressure is admitted into the pipes 35-37 the 20 pistons 28-26 will be moved into the position shown in Figure 2 of the drawings and the fluid pressure will then hold the link sections 17 and 18 in a position to maintain the blank holding member 15 in a position 25 that the blank holder 16 carried by the blank holding member 15 will travel to the full extent or limit of its movement by the links. Obviously the pressure of the fluid under these conditions may be such that the blank 30 holder 16 may be permitted to yield for any desired extent when the blank holder engages the work, but the pressure will be such that the blank holder will be moved into engagement and will exert a working pressure upon the blank.

This construction is advantageous inasmuch as it will permit the blank holder 16 to yield in the event that work of varying thicknesses are placed into the machine after the blank holder has been once set. Furthermore the blank holder 16 will yield in the event that during the drawing operation the work 40 or portions thereof increase in thickness due to the flow of the material 45 from one portion thereof to the other. This yielding of the blank holder 16 will prevent damage to the work as well as to the parts of the mechanism.

It will be obvious that if the blank holder 50 16 is set for a predetermined extent of movement by the links for a blank of a predetermined gauge or thickness and a blank of a larger gauge or thickness is fed into the machine, considerable damage will be 55 caused if the blank holder 16 is not permitted to yield to compensate the varying thicknesses of the work.

If on the other hand, the extent of movement of the blank holder 16 is adjusted so 60 as to accommodate work of one thickness and a blank of a smaller size or gauge is fed into the machine, the blank will not be held with sufficient firmness to prevent the same from wrinkling or becoming distorted and torn during the forming operation.

Therefore, by providing a means whereby the blank holder 16 may automatically adjust itself to compensate the varying thicknesses of the work, these objections will be obviated.

The pressure in the cylinder may be controlled automatically in a manner to be hereinafter set forth.

If desired and under certain conditions when necessary or desirable, the pressure in 75 one or more of the cylinders may be reduced at predetermined times in the cycle of operation of the machine. This may be accomplished by either releasing the pressure in the cylinders on one side of the piston or 80 by exerting another fluid pressure on the other side of the pistons, which is greater than the pressure already exerted thereon, so as to move the pistons in the opposite direction and thereby permit the links 17 and 85 18 to be relatively moved with respect to each other.

This may be accomplished by admitting fluid pressure on the opposite side of the piston 27 through the pipe 39.

Fluid pressure may be supplied from any suitable source such as from a main supply pipe or line 41 leading from which are a plurality of branch pipes or lines 42-43-44, through a suitable controlling device 95 designated generally by the reference numeral 45. This controlling device is provided with suitable valves 46-47 for controlling the direction of flow and the pressure of the fluid and the valves are adapted to be operated from any suitable source either from a moving portion of the machine or from a separate motor (not shown), and which motor imparts motion to a sprocket gear 48, the latter being connected by means of a 100 sprocket chain 49, which passes over another sprocket 50 for operating the valves 46-47, it being understood that a separate operating mechanism is preferable for each 105 of the valves 46-47.

The specific construction and operation of this controlling or valve operating mechanism, however, forms no part of the present invention but constitutes the subject matter of a separate application.

The pipe 42 is connected with the controlling device 45 on one side of the valve 46, and leading from the other side of the valve 46 is a pipe 51, which has communication with the pipe 37 leading to the cylinder 25 on one side of the piston 27. The pipe 44 has communication with the pipe 35, the latter having communication with the chamber 24 on one side of the piston 28. The pipe 43 has communication with the valve 47 on one side thereof and leading from the other side of the valve 47 is a pipe 52 which has communication with the pipe 39, the latter communicating with the chamber 25 on the opposite side of the piston 27.

Suitable pressure regulating valves 53—54—55 may be arranged respectively within the pipe lines 42—43—44. By the provision of these pressure regulating valves the fluid pressure on the respective sides of the respective pistons may be predetermined.

It will therefore be manifest that during the cycle of operation of the press, the valves 46 and 47 will be automatically operated at predetermined points or times in such cycle of operation and by means of such mechanism the pressure of the fluid within the chambers 24 and 25 on the respective sides of the pistons in the cushion may be automatically controlled so that the degree of pressure or stress of the blank holder 16 upon the work may be automatically controlled and the desired pressure may also be controlled, thereby rendering it possible to vary the pressure at different stages in the cycle of operation of the press, and thereby rendering it possible to produce in a single operation of the press shapes and forms of devices which, in order to produce with presses as heretofore constructed and without the use of the present blank holding means, would necessitate several different and distinct operations, necessitating the possible use of two or more different presses.

Furthermore by the use of this invention it is possible with cams or toggle acting presses to hold the material being operated upon at a desired pressure for a predetermined length of time to produce a perfect or clearly defined dwell of the blank holder against the material.

In the form of the invention shown in Figure 4, the link between the crank 16* and the blank holding member 15 embodies a member 56 which is pivotally connected as at 57 with the blank holding member 15 and has connected therewith a cylinder 58, which is provided with a partition 59 dividing the cylinder into two chambers 60—61.

The other member of the link 62 is pivotally connected as at 63 with the crank 16* and extends into the cylinders and through the partition 59. Connected with the member 62 is a piston 64, which is movable within the chamber 61 and a second piston 65 is also connected with the member 62 and is movable within the chamber 60.

A pipe 65* has communication with a passage 66 in the head of the cylinder and has communication with the chamber 60 and corresponds with the pipe 35 in the form of the invention shown in Figure 2. A pipe 67 has communication with a passage 68 leading through the partition 59 and has communication with the chamber 61 on one side of the piston 64 and corresponds with the pipe 37 in the form of the invention shown in Figure 2.

A pipe 69 has communication with a pas-

sage 70 in the head of the cylinder and also has communication with the chamber 61 on the other side of the piston 64 and corresponds with the pipe 39 in the form of the invention shown in Figure 2.

While the preferred forms of the invention have been herein shown and described, it is to be understood that various changes may be made in the details of construction and in the combination and arrangement of the several parts, within the scope of the claims, without departing from the spirit of this invention, and it is to be further understood that although there is shown and described in each form of the invention, two cylinders embodying the cushioning device, this number may be increased or decreased according to the nature of the press and the work to be performed thereon. For these reasons, it is desired that the drawings submitted herewith shall be considered as being merely diagrammatic of the invention.

What is claimed as new is:—

1. Blank holding means, motion creating means, and actuating mechanism for the blank holding means interposed between the latter and the said motion creating means, the said actuating mechanism including a fluid controlled yieldable portion.

2. A machine of the character described including blank holding means, mechanical means for moving the blank holding means into engagement with and for causing the same to exert a working pressure upon the work, the said moving means including a yieldable fluid pressure cushioning device exerting its stress upon the blank holding means, and means for varying the stress of the cushioning device upon the blank holding means.

3. A machine of the character described including blank holding means, mechanical means for moving the blank holding means into engagement with and for causing the same to exert a working pressure upon the work, the said moving means including yieldable fluid pressure mechanism operating to permit the blank holding means to yield with respect to the said moving means to compensate the varying thicknesses of the work.

4. A machine of the character described including blank holding means, mechanical means for moving the blank holding means into engagement with and for causing the same to exert a working pressure upon the work, and fluid pressure yielding means whereby the stress of the said blank holding means upon the work and with respect to the said moving means may be varied at will.

5. A machine of the character described including blank holding means, mechanical means for moving the blank holding means into engagement with and for causing the

same to exert a working pressure upon the work, and fluid pressure yielding means whereby the stress of the said blank holding means upon the work and with respect 5 to the said moving means may be automatically varied to compensate the varying thicknesses of the work.

6. A machine of the character described including blank holding means, and mechanical means for moving the blank holding means into engagement with and for causing the same to exert a working pressure upon the work, the said mechanical means including as a component part thereof 10 of a fluid pressure yielding yieldable section.

7. A machine of the character described including blank holding means, mechanical means for moving the blank holding means into engagement with and for causing the same to exert a working pressure upon the work, the said mechanical means including as a component part thereof a yieldable section, and fluid pressure means for controlling 20 the stress of the said yieldable section.

8. A machine of the character described including blank holding means, mechanical means for moving the blank holding means into engagement with and for causing the same to exert a working pressure upon the work, the said mechanical means including as a component part thereof a yieldable section, and fluid pressure means for controlling the stress of the said yieldable section. 30

9. A machine of the character described including blank holding means, mechanical means for moving the blank holding means into engagement with and for causing the same to exert a working pressure upon the work, the said mechanical means including as a component part thereof a yieldable section, fluid pressure means for controlling the stress of the said yieldable section, and 40 means for controlling the said fluid pressure means.

10. A machine of the character described including blank holding means, mechanical means for moving the blank holding means into engagement with and for causing the same to exert a working pressure upon the work, the said mechanical means including as a component part thereof a yieldable section, and fluid pressure means operating 50 automatically to control the stress of the said yieldable section.

11. A machine of the character described including blank holding means, mechanical means for moving the blank holding means into engagement with and for causing the same to exert a working pressure upon the work, the said mechanical means including as a component part thereof a yieldable section, fluid pressure means for controlling the stress of the said yieldable section, and 60

means operating automatically to control the said fluid pressure means.

12. A machine of the character described including blank holding means, mechanical means for moving the blank holding means into engagement with and for causing the same to exert a working pressure upon the work, the said mechanical means including as a component part thereof a yieldable section, fluid pressure means for controlling the stress of the said yieldable section, and means operating automatically to vary the pressure of the said fluid pressure means at predetermined points in a cycle of operation of the machine. 70

13. A machine of the character described including blank holding means, mechanical means for moving the blank holding means into engagement with and for causing the same to exert a working pressure upon the work, the said mechanical means including as a component part thereof a yieldable section, and fluid pressure means for controlling the stress of the said yieldable section, all 80 of the recited parts being disposed above the work.

14. A machine of the character described including blank holding means, mechanical means for moving the blank holding means into engagement with and for causing the same to exert a working pressure upon the work, the said mechanical means including as a component part thereof a yieldable section, and means for controlling the stress of the said yieldable section, all 90 of the recited parts being disposed above the work. 95

15. A machine of the character described including blank holding means, mechanical means for moving the blank holding means into engagement with and for causing the same to exert a working pressure upon the work, the said mechanical means including a link connected with the blank holding means, said link being sectional, said sections being relatively movable, and fluid pressure yielding means for controlling the relative movement of the link sections. 105

16. A machine of the character described including blank holding means, mechanical means for moving the blank holding means into engagement with and for causing the same to exert a working pressure upon the work, the said mechanical means including a link connected with the blank holding means, said link being sectional, said sections being relatively movable, fluid pressure yielding means for controlling the relative movement of the link sections, and means for varying the stress of the said yielding means. 115

17. A machine of the character described including blank holding means, mechanical means for moving the blank holding means into engagement with and for causing the same to exert a working pressure upon the 120

work, the said mechanical means including a link connected with the blank holding means, said link being sectional, said sections being relatively movable, fluid pressure means for controlling the relative movement of the link sections, and means for automatically controlling the stress of the said yielding means.

18. A machine of the character described including blank holding means, mechanical means for moving the blank holding means into engagement with and for causing the same to exert a working pressure upon the work, the said mechanical means including a link connected with the blank holding means, said link being sectional, said sections being relatively movable, and fluid pressure means for controlling the relative movement of the link sections.

19. A machine of the character described including blank holding means, mechanical means for moving the blank holding means into engagement with and for causing the same to exert a working pressure upon the work, the said mechanical means including a link connected with the blank holding means, said link being sectional, said sections being relatively movable, fluid pressure means for controlling the relative movement of the link sections, and means for controlling the said fluid pressure means.

20. A machine of the character described including blank holding means, mechanical means for moving the blank holding means into engagement with and for causing the same to exert a working pressure upon the work, the said mechanical means including a link connected with the blank holding means, said link being sectional, said sections being relatively movable, fluid pressure means for controlling the relative movement of the link sections, and means controllable at will and operable in opposition to the said fluid pressure means for reducing the stress of the blank holding means upon the work.

21. A machine of the character described including blank holding means, mechanical means for moving the blank holding means into engagement with and for causing the same to exert a working pressure upon the work, the said mechanical means including a link connected with the blank holding means, said link being sectional, said sections being relatively movable, fluid pressure means for controlling the relative movement of the link sections, and fluid pressure means controllable at will and operable in opposition to the first recited fluid pressure means for reducing the stress of the blank holding means upon the work.

22. A machine of the character described including blank holding means, mechanical means for moving the blank holding means into engagement with and for causing the

same to exert a working pressure upon the work, the said blank holding means being movable to a predetermined extent by the second recited means, and means operating to permit the blank holding means to yield with respect to the second recited means and while the stress of the latter is exerted upon the blank holding means.

23. A machine of the character described including blank holding means, mechanical means for moving the blank holding means into engagement with and for causing the same to exert a working pressure upon the work, the said blank holding means being movable to a predetermined extent by the second recited means, and fluid pressure means operating to permit the blank holding means to yield with respect to the second recited means and while the stress of the latter is exerted upon the blank holding means.

24. A machine of the character described including blank holding means, mechanical means for moving the blank holding means into engagement with and for causing the same to exert a working pressure upon the work, the said blank holding means being movable to a predetermined extent by the second recited means, fluid pressure means operating to permit the blank holding means to yield with respect to the second recited means and while the stress of the latter is exerted upon the blank holding means, and means for controlling the pressure of the said fluid pressure means.

25. A machine of the character described including blank holding means, mechanical means for moving the blank holding means into engagement with and for causing the same to exert a working pressure upon the work, the second said means operating to move the blank holding means a predetermined distance upon each cycle of operation of the second recited means, and fluid pressure means whereby the extent of movement of the blank holding means by the second recited means may be varied while the extent of movement of the second recited means remains constant.

26. A machine of the character described including blank holding means, mechanical means for moving the blank holding means into engagement with and for causing the same to exert a working pressure upon the work, the second said means operating to move the blank holding means a predetermined distance upon each cycle of operation of the second recited means, and fluid pressure means whereby the pressure of the blank holding means upon the work may be varied while the extent of movement of the second recited means remains constant.

27. A machine of the character described including blank holding means, mechanical means for moving the blank holding means

- into engagement with and for causing the same to exert a working pressure upon the work, the said mechanical means including a link connected with the blank holding means, and fluid pressure means connected with the link and operating to permit the blank holding means to yield with respect to the work while the stress of the link is exerted upon the blank holding means.
28. A machine of the character described including blank holding means, mechanical means for moving the blank holding means into engagement with and for causing the same to exert a working pressure upon the work, the said mechanical means including
- a link connected with the blank holding means, fluid pressure means connected with the link and operating to permit the blank holding means to yield with respect to the work while the stress of the link is exerted upon the blank holding means, and means controllable at will and operable in opposition to the said fluid pressure for reducing the stress of the blank holding means upon the work.
- In testimony whereof we have signed our names to this specification, on this 7th day of May, A. D. 1923.
- RUDOLPH W. GLASNER.
FREDRICH J. RODE.
